UNITED STATES PATENT OFFICE

1,930,959

VEHICLE LIFTING AND ROTATING APPARATUS

Joseph A. Potvin, St. Remi, Quebec, and Florent Potvin, Montreal, Quebec, Canada

Application April 7, 1933. Serial No. 664,972

3 Claims. (Cl. 254—87)

The present invention relates to apparatus for lifting and rotating automobiles and the like.

An important object of the invention is the provision of vehicle lifting and rotating apparatus designed so that the vehicle may be elevated for replacing or repairing one or more of the wheel tires.

A further object of the invention is the provision of apparatus of the above character constructed so that the vehicle may be elevated and thereafter rotated about the axis of a turntable forming part of the apparatus.

Another object of the invention is the provision of apparatus of the above character embodying a plurality of lifting jacks attached to the vehicle and arranged so that they may be operated singly or in multiple.

Still another object of the invention is the provision of apparatus of the above character which may be so attached to the vehicle as to assume a non-obstructing position when not in use.

A still further object of the invention is the provision of vehicle lifting and rotating apparatus embodying a novel and efficient turntable structure.

Another object of the invention is the provision of apparatus of the above character which will be durable in construction, reliable in operation, and which may be readily attached to conventional types of automobiles.

Other objects and advantages of the invention will become apparent as the description progresses.

In the accompanying drawings forming a part of this specification and in which like reference characters are employed to designate corresponding parts throughout the same:

Figure 1 is a side elevational view of an automobile equipped with the new apparatus, with the front portion of the vehicle in elevated position.

Figure 2 is a front elevational view of the same showing one side of the vehicle elevated.

Figure 3 is a similar view showing the opposite side of the vehicle in opposite arrangement.

Figure 4 is a similar view showing the vehicle completely elevated.

Figure 5 is a top plan view of the vehicle showing, in dotted lines, positions to which the vehicle may be rotated.

Figure 6 is a transverse fragmentary section through the vehicle showing the apparatus attached thereto.

Figure 7 is a horizontal section showing parts of

the vehicle operatively associated with the apparatus.

Figure 8 is a vertical longitudinal section taken diagrammatically through the turntable.

Figure 9 is a fragmentary vertical section showing the drive mechanism.

Figure 10 is a horizontal section taken on the line 10—10 of Figure 9.

Figure 11 is a longitudinal section taken on the line 11—11 of Figure 7.

Figure 12 is a similar view taken on the line 12—12 of Figure 7.

Figure 13 is a vertical central section through one of the lifting jacks in contracted arrangement.

Figure 14 is an enlarged fragmentary section through the same.

Figure 15 is an enlarged horizontal section taken on the line 15—15 of Figure 8.

Figure 16 is a longitudinal section through one of the jacks in extended arrangement.

Figure 17 is an enlarged horizontal section taken on the line 17—17 of Figure 12.

Figure 18 is a longitudinal vertical section through the extensible rotary drive structure.

Figure 19 is an enlarged fragmentary section through the instrument board showing the control mechanism.

Figure 20 is a horizontal section taken on the line 20—20 of Figure 13, and

Figure 21 is a fragmentary vertical section taken on the line 21—21 of Figure 20.

Referring to the drawings, wherein for the purpose of illustration is shown a preferred embodiment of the invention, the letter A generally designates an automobile of conventional construction embodying a chassis 30 and an instrument board 31.

Connected to the chassis 30 through the medium of brackets 33 are a plurality of, in the present instance four, extensible lifting jacks B. Each of the jacks B embodies a cylindrical head section 34 having a partition plate 35 disposed below the top and forming in the head section a gear compartment 36. Depending from the central portion of the partition 35 and rotatably associated therewith is an exteriorly threaded centre screw 37, having the upper part journalled in the partition and the lower threaded part threadedly engaging a second screw section 38. The screw 38 is also exteriorly threaded and is provided with a longitudinal interiorly threaded bore adapted to receive the centre screw 37 therein. The screw section 38 threadedly engages a third screw section 39 likewise interiorly and exteriorly screw-

threaded and operating with an interiorly threaded fourth section 40. As shown to advantage at Figure 14, the exterior threads of the screws 37 and 38 are formed with a continuous groove terminating adjacent the bottom and adapted to receive therein pins 41 attached to the upper ends of the screw sections 38 and 39. The screw 39 is formed with a spiral groove in the shank between the threads to receive therein a pin 42 attached to the upper end portion of the screw section 40. At the lower end of the section 40 is formed a base plate 40' provided with a flange projecting outwardly thereof. At the bottom of the plate 40' is formed a depending ball 43 forming one section 15 of a ball and socket joint.

Three slidably connected telescopic casing sections 44 are connected with the jack head and with the screw sections and are adapted to assume extended positions when the sections are extended to a lifting arrangement. These casing sections are disposed to brace the jacks when they are disposed in extended position.

The lower ends of each of the jacks B are connected with a turntable structure indicated at C. 20 The turntable C embodies a relatively flat circular base plate 46 provided at the peripheral margin with an upwardly offset rim 47. To the centre of the base plate 46 is connected an upwardly projecting pivot bolt 48. Formed concentrically on the plate 46 is an annular interiorly toothed ring gear 49. Rotatably supported on the base plate 46 is a circular top plate 50 having an aperture at the centre through which the pivot bolt 48 is extended and resting on ball bearings 51 30 or any suitable form of friction reducing bearing structure. To the peripheral edge of the top section 50 is connected an annular cover channel 52 covering the edge portion of the base plate 46. At spaced intervals on the top plate 50 are secured socket members 53 adapted to engage the ball sections 43 at the lower ends of the jacks, to provide a universal connection between the jacks and the turntable.

Disposed within and meshing with the ring gear 49 is a drive pinion 55 secured on a vertical spindle projected upwardly through the top plate 50 and attached to the ball section 56 of a ball and socket joint. The pinion 55 is rotated through the instrumentality of an extensible shaft embodying a plurality of longitudinally slidably and telescopic sections 57 connected at the top with a cylindrical head member 58. The extensible jack forming sections 57 are also reinforced by telescopic casing sections 59.

Extending longitudinally adjacent the side bars of the chassis 30 and rotatably journaled thereon are a pair of elongated jack operating shafts 61, extending through the head compartments of the jacks arranged at each side of the chassis. A 55 transversely extending operating shaft 62 is also journaled on bearings attached to the chassis and extends between the side bars thereof. The shaft 62 extends transversely through the head portion 58 of the extensible pinion drive shaft 57. At the intermediate portion of the shaft 62 is secured a worm wheel 63. At both sides of the worm wheel 63 the shaft 62 is equipped with couplings 64, in the present instance embodying frictionally engaging discs pressed into contact by springs. 60 This construction will allow rotary movement of the central shaft section relative to the end sections to obviate undue strain or injury to the jack operating gearing in the event that the driving mechanism is operated longer than is necessary to fully extend the jacks. Adjacent the ends, the

shaft 62 is fitted with worm wheels 65 meshing with worms 66 secured on the side shafts 61 and rotating the latter in unison with the shaft 62.

The worm wheel 63 of the shaft 62 is in mesh with a worm 68 secured on the upper end of a shaft 69 journaled in the top of a gear casing 70. To the lower end of the shaft 69 is secured a bevel gear 71, in mesh with a complementary bevel gear 72 keyed on a shaft 73 journaled longitudinally in the casing 70. A spur gear 74 is also keyed on the shaft 73 and is normally held in a non-operating position by means of a compression spring 75. The gear 74 may be manually shifted through the medium of belt crank and lever mechanism, generally indicated at 76, having connection with a foot pedal 77. When the pedal is depressed, the actuating mechanism 76 will cause the gear 74 to slide on the shaft 73 into mesh with a drive gear 78 driven by the vehicle motor.

On those portions of the shafts 61 extending through each compartment 36 of the jacks is keyed a slidable sleeve 80 having bevel gears 81 secured to each end thereof. The bevel gears 81 may be slidably actuated to alternately mesh with 100 opposed sides of a bevel gear 82 fixed on the upper end of the jack screw 37. A shifting fork 83 engages the sleeve 80 and is rigidly secured to a rock shaft 84. At the outwardly projecting end of the rock shaft is fastened a crank arm 85.

On that portion of the transverse shaft 62 extending through the compartment of the extension shaft head 58 is also keyed a slidable sleeve 87 having bevel gears 88 secured to the ends operable to engage opposite sides of a bevel gear 89 fixed on the upper end of the extensible shaft 57. The sleeve 87 and gears 88 are adjusted through the medium of a rock shaft, a fork attached to the rock shaft engaging the sleeve and an exterior arm corresponding to the shifting 115 mechanism employed to reversibly adjust the gears in the jack transmission means.

Connected to the vehicle chassis 30 and projecting inwardly from opposed sides thereof are a pair of horizontal spindles 91 each supporting 120 thereon a plurality of rotatable levers 92. Four of the levers 92 are connected with rocker arms 85 of the jacks while a fifth lever connects with the rocker arm controlling adjustment of the gears for operating the extension shaft. To each 125 of the levers 92 is connected one end of an operating cable 93 trained over rollers 94. To the opposed end of each cable 93 is connected a push-pull knob 95 adjustably fitted to an instrument board 96. As shown at Figure 19, a spring pressed 130 ball 97 is disposed to engage notches in the shank of each knob 95 to releasably hold the same in adjusted position.

The apparatus is operated as follows:—

To initially lower the turntable C and thereafter elevate the vehicle above the ground, four of the knobs 95 controlling the jack transmission gearing are pulled toward the operator causing one of the bevel gears 81 to engage the bevel gear 82 in each jack compartment. By depressing the 140 foot pedal 77 and operating the vehicle motor, the drive gear train is operatively connected and the screw sections of the jacks are successively rotated to extended arrangement. When the jacks are fully extended the knobs are depressed to an 145 intermediate position.

To rotate the vehicle, as for instance to extricate the same from soft ground or a closely packed parking position, the fifth knob controlling operation of the extension shaft is pulled out- 150

wardly causing one of the bevel gears 88 to mesh with the gear 89 to rotate the extended shaft sections 57 and the spur pinion 55 in a predetermined direction so that the car is horizontally swung about the axis of the turntable base plate 46, as shown to advantage at Figure 5.

If only the front, rear or one side of the car are to be supported in elevated position, two of the jacks are lowered by depressing the corresponding knobs 95 to fully inward positions, permitting coiled tension springs 98 having connection with the rock shaft arms, to shift the jack transmission mechanism so that the opposed bevel gear 81 will engage the drive bevel gear 82 to rotate the shaft screws in a retracting direction so that the two jacks are partially retracted.

It will become apparent that the apparatus is operable to partially or entirely elevate the vehicle and to rotate the same in reverse directions.

It is to be understood that the form of our invention herein shown and described is to be taken as a preferred example of the same, and that various changes as to the shape, size and arrangement of parts may be resorted to without departing from the spirit of the invention or the scope of the subjoined claims.

Having thus described our invention, we claim:—

1. An apparatus of the character described comprising a plurality of extensible lifting members, means for connecting the said members in depending positions with a vehicle, vehicle motor actuated mechanism for individually extending and retracting the said extensible members, a turntable having connection with the lower ends

of the extensible members and supported thereby, the said turntable having a ground engaging base plate and a top plate rotatably supported on the base plate, an annular gear fixed on the base plate, a pinion connected with the top plate and in mesh with the said annular gear, and means for rotating the said pinion to rotate the turntable top plate upon the base plate.

2. An apparatus of the character described comprising a plurality of extensible lifting members, means for connecting the said members in depending positions with a vehicle, vehicle motor actuated mechanism for selectively extending and retracting the said extensible members, a turntable having connection with the lower ends of the extensible members and supported thereby, the said turntable having a ground engaging base plate and a top plate rotatably supported on the base plate, an annular gear fixed on the base plate, a pinion connected with the top plate and in mesh with the said annular gear, and mechanism operable by the vehicle motor for rotating the said pinion to rotate the turntable top plate upon the base plate.

3. In apparatus of the character described, a plurality of extensible jacks, each of said jacks including a plurality of successively extensible screw sections, motor driven mechanism for actuating the said screw sections to extended or to retracted positions, a ground engaging turntable supported by the jacks, and means for selectively actuating any of said jacks.

JOSEPH A. POTVIN.
